UNITED STATES PATENT OFFICE

JOHN A. BROWNLEE, OF CHICAGO, ILLINOIS

SELF-GRADING DEVICE

Application filed July 25, 1929. Serial No. 380,969.

My invention relates to a device adaptable for giving multiple choice tests. One object is to provide a student self-grading device, although I do not wish to be limited to this particular use of the device, since other applications or uses thereof may be made and other objects will appear from time to time in the course of the specification and claims. I illustrate my invention more or less grammatically in the accompanying drawings, wherein—

Figure 1 is a plan view;

Figure 2 is a section on the line 2—2 of Figure 1;

Figure 3 is an enlarged section with one sheet shown in a different position;

Figure 4 is a section on the line 4—4 of Figure 1;

Figure 5 is a section on the line 5—5 of Figure 1;

Figure 6 is a plan view of a code sheet; and

Figure 7 is a score sheet.

Like parts are indicated by like symbols throughout the specification and drawings.

Referring to the drawings, A generally indicates a top face or side of an outer container for the device. It may be folded over or formed with flaps A¹ which underlie the lower member A² of the container. The flaps A¹ may be formed with side portions or spacing portions A³, whereby the members A and A² are spaced apart a suitable distance to permit the insertion therebetween of the sheets later described. I do not wish to be limited to the employment of any particular material, and I may employ, for example, sheet metal, paper, fiber, bakelite and the like.

Referring to the top sheet A, as shown for example in Figure 1 I may provide it with a plurality of aligned apertures. I illustrate for example lines of apertures B arranged, in the form of Figure 1, in vertical lines, each such line being given, if desired, some characteristic symbol, as at B¹. Interposed between each pair of lines of such apertures B is another line of apertures, preferably of like number, and herein shown of somewhat smaller size, as at B². Upon reference to Figure 2 it will be seen that whereas the

larger apertures B have their counter-parts in the apertures B³ of the member A¹, the smaller apertures B² have no such counterparts. It may be desirable, for economy in manufacture, to punch the same apertures all the way through both sheets, but unless it is desired to make the device reversible as to face, the apertures B² are needed only on the top sheet. Whereas I illustrate the apertures of unlike size it will be realized that this is a matter of choice. B⁴ indicates an aperture in the member A, which may serve to reveal the name upon a test sheet inserted within the device. Similarly I may provide an aperture B⁵ to reveal the test number and the aperture B⁶, through which the score or mark may be written upon the sheet. Other apertures, such as B⁷, may be provided, to give space for further marking on the sheet, or to permit other information upon the sheet to show through.

In the employment of the device I may provide a code sheet shown in Figure 6 and generally indicated as C. This sheet may be made to conform in shape to the members A and A² and may be provided at one end with a cut away portion C¹, conforming to a similar cut away portion A¹⁰ in the members A and A². Preferably it is so formed or shaped as to be held against movement in relation to the members A and A² when it is inserted therein. I may for example employ the seals A¹², which pass about the edges of the members A and A² and hold the code sheet against escape or movement through the open end of the device. The sides A⁸, on the other three sides of the device, prevent any lateral movement of the code sheet. I illustrate this method of holding the code sheet fixed as an example of a practical method, but do not wish to be limited specifically thereto except so far as I limit myself precisely by the language of my claims. The sheet C is formed with a plurality of apertures C² aligned with the apertures B and B³ of the members A and A². If desired a mere perforation or weakening of the sheet may be employed to take the place of these apertures, but I prefer to aperture the code sheets to permit the free passage therethrough of whatever punch may be

employed for marking the test or score sheet. Between the successive lines of apertures C^2 , and in line with the apertures B^2 of the member A, the code sheet, when the score sheet is moved, is exposed to the apertures B^2 . In line with such apertures I may have indicating areas, such as the circles C^3 , upon which the correct answer may be indicated, as by coloring the correct area or by inserting any desired marking or symbol.

10 The score sheet D, as shown in Figure 7, may be simply a blank sheet, or it may be provided with a plurality of weakened areas D^1 , adapted to be aligned with the apertures B and B^3 of the members A and A^2 , and of course with the apertures C^2 of the code sheet. The score sheet D is so formed as to be permitted a range of movement within the container formed by the members A and A^2 . 15 Preferably this movement is so proportioned that when the score sheet is in initial position the weakened portions D^1 are aligned with the apertures B , B^3 and C^2 . When the sheet is moved to its final position, the weakened 20 portions D^1 , or the apertures formed by punching them out, are aligned with the apertures B^2 of the member A and the indicating areas C^3 of the code sheet.

In the operation of the device the score 30 sheet is superposed upon the code sheet. It will be seen from Figure 1 that the apertures B are arranged in a plurality of groups or lines, in Figure 1 shown as twenty in number. The number of apertures in each group is 35 constant, being for example shown in Figure 1 as six in each group. In the use of the device a test or set of questions may be propounded in multiple choice form, one question being provided for each group of apertures B, up to twenty, or for any smaller 40 number, if desired. Each such question may be answered by a plurality of alternatives, six or less. Assume for example, in testing color sensitivity, that the first question reads,

45 "What is the color of such and such an object?"

(1) Red. (2) Black. (3) Brown. (4) Green. (5) Blue. (6) Yellow.

The individual taking the test inspects the 50 object and decides that it is yellow and punches out the corresponding hole in the score sheet. If yellow is No. 6 in the list he punches out hole No. 6. He may then move the score sheet D to the right to the position 55 in which it is shown in Figure 3. If he has punched out the correct weakened portion D^1 , it will overlie the marked area on the code sheet. If the student has made a mistake, the punched out area will overlie a 60 blank or unmarked area of the code sheet, and he can, if he wishes, return the score sheet for another test. Students may answer a whole group of such questions and then move the score sheet D to test position, or may 65 make a check after each answer.

The seals A^{12} prevent any tampering with the device or any access on the part of the student to the code sheet. He may employ any desirable means, for instance the point of a pencil, for punching out the weakened areas D^1 . Once he has completed the test he can grade himself and mark his score, for example in the space B^4 , or he can pass the device, still sealed, to the instructor, who can tell at a glance the correct score or mark.

70 The exposed portion of the sheet D is always exposed so that it may be grasped by the fingers of the operator.

75 It will be realized that whereas I have described and shown a practical and operative device, nevertheless many changes might be made in the size, shape, number and disposition of parts without departing from the spirit of my invention. I therefore wish my description and drawings to be taken as in a broad sense illustrative and diagrammatic rather than as limiting me to my specific showing.

80 I claim:

1. In a self grading device of the character 90 described, a container having a front face provided with a first and a second series of apertures, a code sheet positioned within the container and having code indicia aligned with said second series of apertures, a blank 95 sheet interposed between said code sheet and the perforated face of the container, said blank sheet being shiftable to two positions, the respective apertures of the first and second series being aligned in the direction of movement of said blank sheet, the blank sheet in one position being designed to be punctured in alignment with said first series of apertures and then shifted to bring said 100 puncture in alignment with said second series of apertures to thereby render the indicia on the code sheet visible through said second series of apertures in the container face.

105 2. In a self grading device of the character 110 described, a container having a front face provided with a first and a second series of apertures, a code sheet positioned within the container and having code indicia aligned with said second series of apertures, a blank 115 sheet interposed between said code sheet and the perforated face of the container, said blank sheet being shiftable to two positions, the respective apertures of the first and second series being spaced in the direction of movement of the blank sheet an amount corresponding to the extent of movement of said sheet, the blank sheet in one position being designed to be punctured in alignment with said first series of apertures and then shifted to bring said puncture in alignment with said second series of apertures to thereby render the indicia on the code sheet visible through said second series of apertures in the container face.

3. In a self grading device of the character described, a container having a front face provided with a first and a second series of apertures, a code sheet positioned within the container and having code indicia aligned with said second series of apertures, a blank sheet interposed between said code sheet and the perforated face of the container, said blank sheet being shiftable to two positions, the respective apertures of the first and second series being aligned and spaced in the direction of movement of the blank sheet an amount corresponding to the extent of movement of said sheet, the blank sheet in one position being designed to be punctured in alignment with said first series of apertures and then shifted to bring said puncture in alignment with said second series of apertures to thereby render the indicia on the code sheet visible through said second series of apertures in the container face.

4. In a self grading device of the character described, a container having a front face provided with a first and a second series of apertures, the apertures of the two series differing in size, a code sheet positioned within the container and having code indicia aligned with said second series of apertures, a blank sheet interposed between said code sheet and the perforated face of the container, said blank sheet being shiftable to two positions, the blank sheet in one position being designed to be punctured in alignment with said first series of apertures and then shifted to bring said puncture in alignment with said second series of apertures to thereby render the indicia on the code sheet visible through said second series of apertures in the container face.

5. In a self grading device of the character described, a container having a front face provided with a first and a second series of apertures, the apertures of said second series being smaller than the apertures of said first series, a code sheet positioned within the container and having code indicia aligned with said second series of apertures, a blank sheet interposed between said code sheet and the perforated face of the container, said blank sheet being shiftable to two positions, the blank sheet in one position being designed to be punctured in alignment with said first series of apertures and then shifted to bring said puncture in alignment with said second series of apertures to thereby render the indicia on the code sheet visible through said second series of apertures in the container face.

6. In a self grading device of the character described, a container having a front face provided with a first and a second series of apertures, the corresponding apertures of each series being positioned adjacent one another, identifying indicia associated with the apertures of the first series, a code sheet fixed

within the container and having code indicia aligned with said second series of apertures, a blank sheet interposed between the code sheet and apertured face of the container and shiftable with reference to the code sheet, said blank sheet in one position being designed to be punctured in alignment with the first series of apertures and then shifted to bring said puncture in alignment with said second series of apertures to render the code indicia on the code sheet visible through said second series of apertures.

7. In a grading device of the character described, a container provided with a front wall having a first and a second series of apertures, a code sheet positioned within the container and having code indicia aligned with said second series of apertures, said code sheet also provided with a series of apertures aligned with said first mentioned series of apertures in the front wall of the container, a blank sheet interposed between the code sheet and the front wall of the container and shiftable with reference to the code sheet, said blank sheet being designed to be punctured in one of its positions in alignment with the apertures of the first mentioned series and then shifted to its second position to bring said puncture in alignment with the apertures of the second mentioned series to render visible the code indicia on said code sheet, the portion of the blank sheet dislodged by puncture passing through the aperture of the code sheet.

8. In a self grading device of the character described, a container provided with a front wall having a first and a second series of apertures, said container also having a rear wall provided with a series of apertures aligned with the apertures on the first mentioned series, a code sheet fixed within the container and having a series of apertures aligned with the first mentioned series of the front wall of the container and having indicia aligned with the second mentioned series of apertures of the front wall, a blank sheet interposed between the code sheet and perforated front wall of the container, said blank sheet being shiftable to two positions, the blank sheet in one position being designed to be punctured in alignment with the first series of apertures in the front wall of the container and then shifted laterally to align said puncture with the apertures of the second series of apertures in the front wall to render visible the code indicia on the code sheet, the portion of the blank sheet dislodged by said puncturing operation passing through the aligned apertures of the code sheet and rear wall on the container.

9. In a self grading device of the character described, a container having a front wall provided with a first and a second series of apertures, a code sheet fixed with the container and having code indicia aligned with

the second series of apertures, a blank sheet interposed between the code sheet and the perforated front wall of the container and shiftable to two positions, said blank sheet
5 being provided with a series of scored portions aligned with the first series of apertures in one position and alignable with the second series of apertures in another position, said blank sheet being designed to be punctured
10 in its first position whereby said puncture may be aligned with certain code indicia on the code sheet in another position to render said code indicia visible through the second series of apertures in the front wall of the
15 container.

Signed at Chicago, county of Cook and
State of Illinois, this 20th day of July, 1929.
JOHN A. BROWNLEE.
